UNITED STATES PATENT OFFICE.

FREDERICK DREYER, OF CHICAGO, ILLINOIS, ASSIGNOR OF ONE-HALF TO DORA DOSSE,
OF CHICAGO, ILLINOIS.

BOX OPENER.

1,409,367.

Specification of Letters Patent. Patented Mar. 14, 1922.

Application filed April 5, 1920. Serial No. 371,333.

To all whom it may concern:

Be it known that I, FREDERICK DREYER, a citizen of the United States, and a resident of the city of Chicago, county of Cook, and State of Illinois, have invented certain new and useful Improvements in Box Openers, of which the following is a specification.

My invention relates to improvements in box openers especially adapted for use on blacking boxes, and has for its object the provision of an improved device of this character which is of simple construction and efficient in use.

Other objects will appear hereinafter.

The invention consists in the combinations and arrangements of parts hereinafter described and claimed.

The invention will be best understood by the accompanying drawings forming a part of this specification, and in which,

Fig. 1, is a side view of a box equipped with an opener embodying the invention,

Fig. 2, a top plan view of the same,

Fig. 3, a partial side view of the box showing the opener in one end elevation, and

Fig. 4, a similar view showing the opener in its other end elevation and in operative position for removing the lid.

The preferred form of construction, as illustrated in the drawings, comprises a box body 5, removable lid 6, and stop bead 7, the same constituting the ordinary form of box for containing blacking or the like. A supporting lip 8 is formed at or secured to one side of the lid 6 adjacent the bead 7, and a cam lever 9 is pivotally mounted on the under side of the lip 8 by means of a rivet 10 forming a pivot axis extending substantially parallel to the adjacent side of the box. The cam lever 9 is in channel form, as shown, one portion of said channel being notched or cut away and formed into a cam surface 11 adapted to rub against the stop bead 7 of the box when said lever is turned.

The arrangement is such that when the lever 9 is thrown outwardly from the position indicated in Fig. 2, to the position indicated in Fig. 4, the cam surface 11, rubbing against the stop bead 7, forces the lid 6 upwardly to permit of ready removal thereof. By this arrangement, the lever 9 is held in accurate and constant contact with the bead 7 during operation, and there is no way in which said lever can slip or spring

over said bead without forcing the lid upwardly. The action attained is positive and effective for the purpose, and powerful leverage is exerted by the cam action to effect the removal of the lid.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. In combination with a receptacle having a lid; a bearing member mounted adjacent said lid; a horizontally swinging lever mounted on said lid; and an inclined surface on said lever adapted to ride on said bearing member to force the lid from said receptacle when the lever is operated.

2. In combination with a receptacle having a lid; a bearing member mounted adjacent said lid; a horizontally swinging lever on said lid; and a cam surface on said lever having a gentle initially engaging steeply increasing curvature adapted to ride on said bearing member and force the lid from said receptacle when the lever is operated.

3. In combination with a receptacle having a bead and a lid engaging said bead; a lever mounted on said lid and swinging in a horizontal plane; and a cam surface on said lever having a gentle initially engaging steeply increasing curvature adapted to ride on said bead and force the lid from said receptacle when the lever is operated.

4. In combination with a receptacle having a bead and a lid engaging said bead, an opener comprising a lip attached to said lid and projecting laterally therefrom; a lever pivoted on said lip and adapted to swing in a horizontal plane; and a cam surface on said lever adapted to ride on said bead to force the lid from the receptacle when the lever is operated, substantially as described.

5. In combination with a receptacle having a bead and a lid engaging said bead, an opener comprising a lip attached to said lid and projecting horizontally therefrom; a

lever pivoted on said lip to swing in a horizontal plane and when in inoperative position engaging the side of said receptacle; and a cam surface on said lever adapted to ride on said bead and force the lid from said receptacle when the lever is swung outwardly, substantially as described.

In testimony whereof I have signed my name to this specification in the presence of two subscribing witnesses.

FREDERICK DREYER.
